UNITED STATES PATENT OFFICE.

CHARLES F. GREEN, OF DEFIA, OHIO, ASSIGNOR TO INDUSTRIAL RESEARCH CORPORATION, OF TOLEDO, OHIO, A CORPORATION OF DELAWARE.

FUEL-FEED SYSTEM.

1,352,123.

Specification of Letters Patent. Patented Sept. 7, 1920.

Application filed November 14, 1918. Serial No. 262,532.

To all whom it may concern:

Be it known that I, CHARLES F. GREEN, residing at Defiance, in the county of Defiance and State of Ohio, have invented certain new and useful Improvements in Fuel-Feed Systems, of which I declare the following to be a full, clear, and exact description.

My invention relates to a fuel feed system and has for its object to provide improved means for transferring fuel from a relatively low to a relatively high level, and is particularly adapted for forcing fuel from the main fuel supply tank of a motor driven vehicle to the carburetor thereof.

A still further object of the invention is to provide a combined and improved feed system for supplying both fuel and lubricating material to the engine of a motor driven vehicle.

Another object of the invention is to provide a pump adapted to be driven from the engine for supplying both fuel and lubricating material thereto.

A further object of the invention is to provide improved means for maintaining a constant level of fuel in the carburetor or other receptacle from which the fuel may be fed to the engine.

A still further object of the invention is to provide a fuel feed system comprising an improved suction-controlled apparatus interposed between the carburetor and fuel supply source of an automobile engine, including means to effect return through the connection between the supply source and carburetor of any excess fuel over and above the amount required to maintain a constant level in the carburetor.

To these and other ends the invention comprises certain novel features of construction and arrangement of parts, as will be hereinafter more fully described and claimed, it being understood that various modifications in the present structure may be made without departing from the spirit of the invention.

In the present application I have shown one embodiment of my invention, in which: Figure I is a diagrammatic view in elevation illustrating the preferred manner of carrying out the invention.

Fig. II is an enlarged sectional elevation

through the carburetor and valves controlling the supply of fuel thereto, and

Fig. III is a sectional elevation through the pump taken on line III-III of Fig. I.

Like reference characters indicate like parts in the several views of the drawings.

Referring to the drawings, 10 represents a motor or engine having a carburetor 11 of any preferred type connected with the main low level fuel supply tank 12, by means of the conduit 13 from which extends the pipe or conduit 14 connected with a pump 15, as shown in Fig. I.

The crank casing 16 which is preferably used for holding a supply of lubricating material for the engine, is connected with the intake side of the pump by means of the conduit 17 and valve casing 18, while the discharge side of the pump is connected with the engine proper by means of the conduit 19 and threaded connection 20 shown in Fig. III.

The pump is preferably bolted to the exterior of the engine casing and provided with a cylinder or sleeve 21 projecting inwardly and carrying a piston 22 arranged to be actuated in one direction by any suitable moving part of the engine as by the cam 23 on the engine cam shaft 24. The piston is preferably made hollow and is provided with a plunger 25 on which is mounted a spring 26 serving to actuate the piston outwardly, after said piston has reached the limit of its inward movement when actuated by the cam. By this means the piston is reciprocated in the oil receiving chamber 27 of the pump into which lubricating material is drawn past the spring pressed valve 28 on the suction stroke of the piston, and from which it is discharged past the spring pressed valve 29 through the passageway 30, connection 20, conduit 19 to the engine to be circulated therethrough back to the crank casing 16.

The plunger 25 is provided with an extension forming a piston 31 adapted to be reciprocated in the bore or recess 32 of the pump which communicates with the suction conduit 14 through the short pipe 33 screwed into the bore 32 of the pump.

The fuel receiving chamber 34 in which it is desired to maintain a constant head of fuel may form a portion of the carburetor.

reter or may be an independent receptacle connected with the carbureter, but in the present instance it comprises the carbureter float chamber having a fuel outlet passageway 35 connected with any suitable type of vaporizing device such as that indicated at 36, which is preferably extended into the supply pipe or conduit 37 for supplying the vaporized fuel to the intake manifold of the engine, not shown.

The float chamber 34 preferably at the bottom thereof is connected with the fuel supply pipe or conduit 13 by means of the four-way connection shown in section in Fig. II, which is provided with the upper and lower threaded valve casings 38 and 39 respectively, the latter having a non-return inlet valve 40 normally held closed by a light spring 41 while the upper casing 38 is provided with a discharge valve 42 which is free to move therein a limited amount, but which is intermittently held seated by means which will presently be described.

The right-hand portion 43 of the four-way connection shown in Fig. II forms a valve casing for the overflow valve 44 which is normally held seated by the spring 45 having a greater resistance to compression than the fuel inlet valve spring 41. A by-pass or overflow pipe 46 is connected at its upper end with the valve casing 43 by means of the coupling 47 and is connected at its lower end to the fuel supply pipe 13 by means of the coupling 48.

The conduits 13 and 14 are connected with said four-way member by the couplings 49 and 50 respectively, as clearly shown in Fig. II.

Mounted in the chamber 34 of the carbureter or other receptacle is a float 51 carried by the long arm 52 of the horizontally disposed lever pivoted intermediate its ends at 53, the short arm 54 of which is pivotally connected at 55 to a downwardly extending rod or member 56 projecting loosely through a guide 57 into the valve chamber 58 in which the fuel inlet valve 42 is mounted for intermittently closing the passageway 59 of said four-way connection.

In the operation of my improved feed system for supplying fuel and lubricating material to the engine, upon rotation of the cam 23, both the large and small pistons 22 and 31 will be reciprocated in their respective cylinders, suction being simultaneously produced in the conduits 13 and 17 for lifting the lubricating material therein to the pump, in one case, and the fuel to the four-way casing in the other. On the compression stroke of the piston 22 the ball valve 28 will remain seated and the ball valve 29 opened, at which time the lubricating material is forced from the chamber 27 through the passageway 30, connection 20, and conduit 19 to the engine, from

whence it finds its way back to the crank casing 16, or other suitable source which may be provided. Likewise on the compression stroke of the relatively small piston 31 the fuel which has been drawn into the four-way connection will be forced upwardly therefrom or forwardly in the sense of toward the chamber 34 through the passageway 59 past the ball valve 42 and into the float chamber 34. However, when the fuel has reached a predetermined level in said float chamber, the rod 56 will be moved down by the arm 54 of the float lever as the float is elevated by the rise of the liquid in the float chamber. In this way the valve 42 is intermittently held closed by the rod 56 but only momentarily, as the engine is constantly consuming fuel from the chamber 34 and, therefore, the position of the float in the chamber will be changed from time to time within certain limits, although the height of the fuel in said chamber is maintained at substantially a constant level. For the period of time during which the valve 42 is held closed by the member 56 all of the fuel drawn into the four-way connection will be forced therefrom through the by-pass 46 and back to the supply pipe 13, for the reason that the spring 45 offers less resistance to the valve 44 than the float actuated rod to the fuel inlet valve 42.

In the claims I have referred to the check valve 42 as the upper check valve, and to the check valve 40 as the lower check valve, and have defined both of these valves as opening upwardly and the check valve 44 as opening downwardly. I desire to have it understood, however, that these terms are intended to be construed in a broad sense, that is, in such a way as to cover the arrangement of valve 42 and 40 as upon the sides of the four-way passage toward and away from the float chamber respectively, and opening toward that chamber while the check valve 44 opens backwardly or away from the float chamber. Whether the three valves be all arranged in one vertical plane or not is immaterial, nor is it necessary that the check valve 40 be positioned beneath the check valve 42 so long as they occupy the relative positions in the pipe connection 13 shown in the drawing.

Having thus described my invention, what I claim as new and desire to secure by Letters Patent, is:

1. A device of the class described comprising a receptacle having inlet and outlet passageways leading to and from the same, a check valve in said inlet passageway opening in the direction of the receptacle, an arm pivotally mounted in the receptacle having a float thereon, a slidably mounted member pivotally connected with said arm and normally independent of said valve and adapted to hold the same closed when said

float is moved to a predetermined position in said receptacle.

2. A device of the class described, comprising a receptacle having inlet and outlet passageways leading to and from the same, a check valve in said inlet passageway opening in the direction of the receptacle, an arm pivotally mounted in the receptacle having a float thereon, a rod pivotally connected with said arm adapted to hold said valve closed when said float is moved to a predetermined position in said receptacle, a guide for said rod, and a vaporizer connected with said outlet passageway.

3. In a fuel feed system for automobiles, a low level tank, a high level receptacle, a pipe connection between the two, an upwardly opening check valve in said connection between said receptacle and pipe, a second upwardly opening check valve below said first valve and spaced therefrom, means for producing suction and compression impulses in the pipe between said check valves, a by-pass around said lower check valve, float controlled means for holding said upper check valve closed when the fuel in the receptacle reaches a predetermined level, and a downwardly opening check valve in said by-pass adapted to open only when said upper check valve is held closed.

4. In a fuel feed system for automobiles, a low level tank, a high level receptacle, a pipe connection between the two, an upwardly opening check valve at the junction of said receptacle and pipe, a second up-

wardly opening check valve below said first valve and spaced therefrom, means for producing suction and compression impulses in the pipe between said check valves, a by-pass around said lower check valve, a movable element for holding said upper check valve closed, a float in said receptacle for actuating said element when the fuel in the receptacle reaches a predetermined level, and a downwardly opening check valve in said by-pass adapted to open only when said upper check valve is held closed.

5. In a fuel feed system for automobiles, a low level tank, a high level receptacle, a pipe connection between the two, an upwardly opening check valve at the junction of said receptacle and pipe, a second upwardly opening check valve below said first valve and spaced therefrom, means for producing suction and compression impulses in the pipe between said check valves, a by-pass around said lower check valve, a vertically sliding element positioned above said upper check valve, a float in said receptacle, connections between said float and sliding element arranged to cause the latter to descend and hold the upper check valve closed when the float rises to a predetermined level, and a downwardly opening check valve in said by-pass adapted to open only when said upper check valve is held closed.

In testimony whereof I affix my signature.

CHARLES F. GREEN.
